**HYDROQUINONYLSULFONYL AZO DYE
DEVELOPERS**

Milton Green, Newton Center, Mass., assignor to
Polaroid Corporation, Cambridge, Mass., a corpora-
tion of Delaware
No Drawing. Filed Oct. 12, 1962, Ser. No. 230,288
3 Claims. (Cl. 260—162)

This application is in part a continuation of my co-
pending application, Serial No. 680,434, filed August
26, 1957, now abandoned.

This invention relates to photography and more particu-
larly to products, compositions and processes for the
development of photosensitive silver halide elements.

It is one object of the present invention to provide novel
processes and compositions for the development of silver
halide emulsions, in which colored developing agents are
used to develop a latent image.

Another object is to provide novel processes and com-
positions for the development of silver halide emulsions,
in which the novel developing agent is capable of de-
veloping a latent image and imparting a reversed or positive
colored image of said latent image to a superposed
image-receiving material.

A further object is to provide novel products, processes
and compositions suitable for use in preparing mono-
chromatic and multichromatic photographic images.

Other objects of the invention will in part be obvious
and will in part appear hereinafter.

The invention accordingly comprises the processes in-
volving the several steps and the relation and order of
one or more of such steps with respect to each of the
others, and the products and compositions possessing the
features, properties and the relation of elements which are
exemplified in the following detailed disclosure, and the
scope of the application of which will be indicated in the
claims.

The novel photographic developing agents employed in
this invention possess the properties of both a dye and a
developing agent; thus they may be referred to as dye
developers. The nature of these dye developers will be
described hereinafter.

The photographic processes and compositions disclosed
herein are particularly useful in the treatment of an
exposed silver halide emulsion, whereby a positive dye
image may be imparted to another element, herein re-
ferred to as an image-carrying or image-receiving element.

U.S. Patent No. 2,983,606, issued May 9, 1961 to
Howard G. Rogers, discloses diffusion transfer processes
wherein a photographic negative material, such as a photo-
graphic element comprising an exposed silver halide emul-
sion is developed in the presence of a dye developer to im-
part to an image-receiving layer a reversed or positive dye
image of the developed image by permeating into said
emulsion layer a suitable liquid processing composition
and bringing said emulsion layer into superposed rela-
tionship with an appropriate image-receiving layer.

It is an object of this invention to provide additional
dye developers suitable for use in such processes.

In carrying out the process of this invention, a photo-
sensitive element containing a silver halide emulsion is
exposed and wetted with a liquid processing composition,
for example, by immersing, coating, spraying, flowing,
etc., in the dark, and the photosensitive element super-
posed, prior to, during or after wetting, on an image-
receiving element. In a preferred embodiment, the photo-
sensitive element contains a layer of dye developer, and
the liquid processing composition is applied to the photo-
sensitive element in a uniform layer as the photosensi-
tive element is brought into superposed position with an

2

image-receiving element. The liquid processing composi-
tion permeates the emulsion to provide a solution of dye
developer substantially uniformly distributed therein. As
the exposed silver halide emulsion is developed, the oxida-
tion product of the dye developer is immobilized or pre-
cipitated in situ with the developed silver, thereby pro-
viding an imagewise distribution of unoxidized dye de-
veloper dissolved in the liquid processing composition.
This immobilization is apparently, at least in part, due
to a change in the solubility characteristics of the dye de-
veloper upon oxidation, and especially as regards its solu-
bility in alkaline solutions. It also may be due, in part,
to a tanning effect on the emulsion by the oxidized de-
veloping agent. At least part of this imagewise distribu-
tion of unoxidized dye developer is transferred, by im-
bibition, to a superposed image-receiving layer. Under
certain circumstances, the layer of the liquid processing
composition may be utilized as the image-receiving layer.
The image-receiving layer receives a depthwise diffusion,
from the emulsion, of unoxidized dye developer, without
appreciably disturbing the imagewise distribution thereof,
to provide a reversed or positive, colored image of the
developed image. The image-receiving element may con-
tain agents adapted to mordant or otherwise fix the dif-
fused, unoxidized dye developer. If the color of the dif-
fused dye developer is affected by changes in the pH of
the image-receiving element, this pH may be adjusted in
accordance with well-known techniques to provide a pH
affording the desired color. Imbibition periods of ap-
proximately one minute have been found to give good
results, but this contact period may be adjusted where
necessary to compensate for variations in temperature or
other conditions. The desired positive image is revealed
by stripping the image-receiving element from the photo-
sensitive element at the end of the imbibition period.

The dye developers of this invention may be utilized in
the photosensitive element, for example in, on or behind
the silver halide emulsion, or they may be utilized in the
image-receiving element or in the liquid processing com-
position. In a preferred embodiment, a coating or layer
of the dye developer is placed behind the silver halide
emulsion, i.e., on the side of the emulsion adapted to be
located most distant from the photographed subject when
the emulsion is exposed and preferably also adapted to be
most distant from the image-receiving element when in
superposed relationship therewith. Placing the dye de-
veloper behind the emulsion layer, as in the preferred em-
bodiment, has the advantage of providing increased con-
trast in the positive image, and also minimizes any light-
filtering action by the colored dye developer. In this
preferred embodiment, the layer of dye developer may be
applied by using a coating solution containing about 0.5
to 8%, by weight, of the dye developer. Similar concen-
trations may be used if the dye developer is utilized as a
component of the liquid processing composition. In an
especially useful mode of dispersing the dye developers in
the photosensitive elements, the dye developer is dissolved
in a water-immiscible solvent and then dispersed in a gela-
tin coating solution.

The liquid processing composition above referred to
comprises at least an aqueous solution of an alkaline com-
pound, for example, diethylamine, sodium hydroxide or
sodium carbonate, and may contain the dye developer. In
some instances, it may contain a minor amount of a con-
ventional developing agent. If the liquid processing com-
position is to be applied to the emulsion by being spread
thereon, preferably in a relatively thin, uniform layer, it
may also include a viscosity-increasing compound con-
stituting the film-forming material of the type which, when
said composition is spread and dried, will form a rela-
tively firm and relatively stable film. A preferred film-

forming material is a high molecular weight polymer such as a polymeric, water-soluble ether inert to an alkali solution, as, for example, a hydroxyethyl cellulose or sodium carboxymethyl cellulose. Other film-forming materials or thickening agents whose ability to increase viscosity is substantially unaffected when left in solution for a long period of time may also be used.

The novel dye developers of this invention may be represented by the formula:

wherein Ar is an aryl nucleus, such as a benzene or naphthalene nucleus; each Z is an alkoxy group, an alkyl group, preferably a lower alkyl group such as methyl or ethyl, or a halogen such as chlorine; m is 0 or 1; u is 0, 1, 2 or 3; v is 0, 1 or 2; p is 1 or 2; Y is a p-dihydroxyphenyl, or a p-bis-acyloxyphenyl group; and X_a and X_b are each the radical of an azo coupling component, which coupling component may be the same or different.

In a preferred embodiment the aryl nucleus is a benzene nucleus, and such dye developers may be represented by the formula:

wherein Y, Z, u, v, m, p, X_a and X_b have the same meaning as above.

As illustrations of suitable azo coupling components or couplers from which X_a and X_b may be derived, mention may be made of phenols and aromatic amines having a free position ortho or para to the hydroxyl or amino group, e.g., phenol, anilines, naphthols, anthrols, naphthylamines, etc.; heterocyclic aromatic compounds containing hydroxyl or amino groups, such as pyrazolones or pyrroles; aliphatic or alicyclic activated methylene couplers, i.e., compounds having an aliphatic or alicyclic methylene group activated by two adjacent keto, aldehyde, ester or nitrile groups, which may be the same or different, or a keto, aldehyde, ester or nitrile group in combination with an amide group, e.g., 1,3-diketones or β -ketonic acid arylamides; etc., and substituted derivatives thereof. Examples of groups which may be present in such substituted derivatives include alkyl, sulfo, alkoxy, aryl, aryloxy, amino, keto, alkylamino, arylamino, hydroxyl, cyano, alkylamido, arylamido, carbalkoxy, carboxamido, sulfonamido, etc.

As used herein with reference to X_a and X_b, the expression "radical of a phenolic coupler" is intended to refer to hydroxyphenyl, hydroxynaphthyl, hydroxyanthryl, etc. radicals, and substituted derivatives thereof; the expression "radical of an aromatic amino coupler" is intended to refer to aminophenyl, aminonaphthyl, etc. radicals, and substituted derivatives thereof; and the expressions "radical of a heterocyclic aromatic coupler," "radical of an aliphatic activated methylene coupler" and "radical of an alicyclic activated methylene coupler" are to be similarly construed.

The novel dye developers of this invention may be prepared by diazotizing a compound of the formula:

wherein Y, Z, m, u, v and X_a have the same meaning as above, and coupling the diazotized compound (C) into the desired coupling components providing X_b.

The compounds of Formula C, wherein m is 0, e.g., p-aminophenylsulfonyl-hydroquinone, may be prepared according to the procedure of Burton and Hogsarth, JACS 1945, page 468. The hydroxyl groups may be protected during the diazotization and coupling reactions by the use of protective derivatives, e.g., acyl groups, of said hydroxyl groups. Such acylated compounds may be pre-

pared according to the procedure disclosed and claimed in U.S. Patent No. 3,019,254, issued January 30, 1962 to Milton Green and Helen P. Husek. The monoazo intermediates may be made as disclosed herein and may be employed without removal of such protective groups in subsequent diazotization and coupling steps.

The preferred compound within the group represented by Formula C is:

15 The coupling is generally performed at a pH which is preferably not greater than about 9. The hydroxy groups of Y are protected during diazotization and coupling, as by the use of a bis-acyloxy derivative as mentioned above.

20 By the use of two moles of the diazonium salt to each mole of the coupling component, one may couple twice into certain of the coupling components which provide the radical X_b, as, for example, phenols and aromatic amines which have two directing groups and two free coupling positions, such as 1,6-dihydroxy naphthalene and 1,5-diaminonaphthalene.

25 Where the coupling component is a phenolic coupler, and particularly a naphthol, it has been found that coupling ortho to the hydroxyl group gives a dye developer of superior color properties.

30 As examples of suitable dye developers within the scope of this invention, mention may be made of the following:

The novel dye developers within the scope of this invention gives generally brighter dye images in the diffusion transfer process than many other azo dye developers. This unobvious property may be illustrated by the compound of Formula II which compound is a brighter dye than 2-[p-(2',5'-dihydroxyphenethyl)-phenylazo]-4-methoxy-1-naphthol employing the same azo coupler, disclosed and claimed in the copending application of Elkan R. Blout, Milton Green and Howard G. Rogers, Serial No. 144,816, filed October 18, 1961, now U.S. Patent No. 3,134,672, and also fades to a magenta shade that is brighter than the shade of the above-mentioned 2-[p-(2',5'-dihydroxyphenethyl)-phenylazo]-4-methoxy-1-naphthol after both dyes have been exposed to accelerated fading conditions for an equal period. It should also be noted that the "muddy" or dull appearance frequently found in dye developers such as the above-identified 2-[p-(2',5'-dihydroxyphenethyl)-phenylazo]-4-methoxy-1-naphthol after such accelerated fading tests is not found in the dye developers of this invention. In other words, the dye developer of Formula II fades to shades of magenta without the appearance of undesirable dull color characteristics which may be described as muddying, but rather retains the brightness characteristics originally found in the dye before fading.

The dye developers of this invention are pH sensitive since the sulfonyl linking group is not an insulating group and therefore care must be taken in the utilization of such dye developers to provide a pH which will afford the desired color.

The dye developers of this invention are less active dye developers than, for example, the dye developers of the above-mentioned application Serial No. 144,816, and are therefore useful where such a diminished degree of activity is desired.

The following examples of the preparation of dye developers within the scope of this invention by diazotizing and coupling compounds within Formula C are given for the purposes of illustration only.

Example 1

2.9 g. of p-aminophenylsulfonyl-hydroquinone-O,O'-diacetate (0.0083 mol) is dissolved in 20 cc. of water and 25 cc. of glacial acetic acid by heating. The mixture is cooled to about 10° C. and 0.66 cc. of 12.5 N hydrochloric acid (0.0083 mol) is added. The resultant mixture is cooled in an ice bath and diazotized with sodium nitrite. The resulting diazo slurry is added, with constant stirring, to a mixture of 1.4 g. of 1-phenyl-3-methyl-5-pyrazolone (0.008 mol), 20 cc. of pyridine, 50 cc. of water, and 20 cc. of saturated sodium bicarbonate solution, concurrently with sufficient 10% sodium carbonate solution to maintain a pH of 7 to 8. The resulting slurry is stirred for about 2 hours at room temperature, filtered and washed with water. The acetyl groups are removed by hydrolysis in vacuo with 3 g. of 85% potassium hydroxide, 10 cc. of water, 40 cc. of ethanol and heating for a few minutes on a steam bath. The resulting mixture is cooled, poured into a dilute hydrochloric acid solution and then filtered. The precipitate is purified by dissolving it in methyl Cellosolve and reprecipitating with a 1% hydrochloric acid solution to yield 1.4 g. of 1-phenyl-3-methyl-4-[p-(hydroquinonylsulfonyl)-phenylazo]-5-pyrazolone [Formula I], M.P. 235 to 237° C. The absorption spectrum of this product exhibits a λ_{max} of 390 m μ in acetone, $\epsilon=27,000$.

Example 2

4 g. of p-aminophenylsulfonyl-hydroquinone-O,O'-diacetate (0.0115 mol) is dissolved in 30 cc. of glacial acetic acid and 0.92 cc. of 12.5 N hydrochloric acid by heating to a boil. The mixture is cooled in an ice bath and diazotized with sodium nitrite. The resultant clear diazo solution is added to 30 cc. of an ice water mixture and the resultant diazo slurry is added with constant stir-

ring, to a mixture of 1.4 g. of 4-methoxy-1-naphthol (0.008 mol), 70 cc. of acetone, 40 cc. of saturated sodium bicarbonate solution, 20 cc. of pyridine, and 40 cc. of water, concurrently with sufficient 10% sodium carbonate to maintain a pH of 7 to 8. The resulting slurry is stirred for about 2 hours at room temperature, diluted with water and the mixture decanted yielding a gum product. The acetyl groups are removed by hydrolysis in vacuo with 4 g. of 85% potassium hydroxide, 80 cc. of ethanol, 15 cc. of water and heating for a few minutes on a steam bath. The resulting mixture is cooled, poured into a dilute hydrochloric acid solution and then filtered. The resulting precipitate is purified by dissolving it in a methyl Cellosolve solution and reprecipitating with water to yield 1.1 g. of 4-methoxy-2-[p-(hydroquinonylsulfonyl)-phenylazo]-1-naphthol [Formula II], M.P. 184 to 188° C. The absorption spectrum of this product exhibits a λ_{max} of 516 m μ in acetone, $\epsilon=20,500$.

In the following examples all parts are given by weight except where otherwise noted, and all operations involving light-sensitive materials are carried out in the absence of actinic radiation. These examples are intended to be illustrative only of the photographic use of the dye developers and should not be construed as limiting the invention in any way.

Example 3

A photosensitive element is prepared by coating a gelatin-coated film base with a solution containing 3% of 1-phenyl-3-methyl-4-[p-(hydroquinonylsulfonyl)-phenylazo]-5-pyrazolone [Formula I as prepared in Example 1], in a 4% solution of cellulose acetate hydrogen phthalate in a 50:50 mixture, by volume, of acetone and tetrahydrofuran. After this coating has dried, a silver iodobromide emulsion is applied.

This photosensitive element is exposed and processed by spreading an aqueous liquid processing composition comprising:

	Percent
40 Sodium carboxymethyl cellulose	6.0
1-phenyl-3-pyrazolidone	0.2
Sodium hydroxide	5.0
Potassium bromide	0.5

between said photosensitive element and an image-receiving element as said elements are brought into superposed relationship. The image-receiving element comprises a cellulose-coated baryta paper which has been coated with a solution comprising 10% Nylon Type F8 (trade name for N-methoxymethyl polyhexamethylene adipamide) in 80% aqueous isopropanol. After an imbibition period of approximately one minute, the image receiving element is separated and contains a yellow positive dye image of the photographed subject.

Example 4

A photosensitive element is prepared similar to that described in Example 3 using 3% of 4-methoxy-2-[p-(hydroquinonylsulfonyl)-phenylazo]-1-naphthol [Formula II as prepared in Example 2]. Exposure and processing with a liquid processing composition and image-receiving element similar to those described in Example 3 give a magenta positive dye image.

The dye developers of this invention are also useful in integral multilayer photosensitive elements for use in multicolor diffusion transfer processes. As an example of such photosensitive elements, mention may be made of the photosensitive elements disclosed and claimed in the copending U.S. application of Edwin H. Land and Howard G. Rogers, Serial No. 565,135, filed February 13, 1956, wherein at least two selectively sensitized photosensitive strata are superposed on a single support and are processed, simultaneously and without separation, with a single common image-receiving element. A suitable arrangement of this type comprises a support carrying a red-sensitive silver halide emulsion

stratum, a green-sensitive silver halide emulsion stratum and a blue-sensitive silver halide emulsion stratum, said emulsions having associated therewith, respectively, a cyan dye developer, a magenta dye developer and a yellow dye developer. In one of the preferred embodiments of photosensitive elements of this type, the dye developers are disposed in separate alkali-permeable layers behind the photosensitive silver halide emulsion stratum with which they are associated.

The photosensitive elements within the scope of this invention may be used in roll film units which contain a plurality of photosensitive frames. The photosensitive elements of this invention are especially useful in composite roll film intended for use in a "Polaroid Land Camera," or a similar camera structure such, for example, as the camera forming the subject matter of U.S. Patent No. 2,435,717, issued to Edwin H. Land on February 10, 1948. In general, such composite roll films comprise a photosensitive roll, a roll of image-receiving material and a plurality of pods containing an aqueous alkaline processing solution. The rolls and pods are so associated with each other that, upon processing, the photosensitive element may be superposed on the image-receiving element and the pods may be ruptured to spread the aqueous alkaline processing solution between the superposed elements. The nature and construction of the pods used in such units are well known to the art. See, for example, U.S. Patents Nos. 2,543,181 and 2,634,886, issued to Edwin H. Land.

It will be noted that the liquid processing composition may contain one or more auxiliary or accelerating silver halide developing agents, such as p-methylaminophenol (Metol); 2,4-diaminophenol (Amidol); benzylaminophenol; hydroquinone; a substituted hydroquinone such as tolhydroquinone, phenylhydroquinone, or 4'-methylphenylhydroquinone; or a 3-pyrazolidone such as 1-phenyl-3-pyrazolidone. These silver halide developing agents are substantially colorless, at least in their unoxidized form. It is possible that some of the dye developer oxidized in exposed areas may be oxidized by an energy transfer reaction with oxidized auxiliary developing agent.

In addition, development may be effected in the presence of an onium compound, particularly a quaternary ammonium compound, in accordance with the processes disclosed and claimed in the copending application of Milton Green and Howard G. Rogers, Serial No. 50,851, filed August 22, 1960.

The dye developers of this invention may be used also in conventional photographic processes, such as tray or tank development of conventional photosensitive films, plates or papers to obtain black and white, monochromatic or toned prints or negatives. By way of example, a developer composition suitable for such use may comprise an aqueous solution of approximately 1-2% of the dye developer, 1% sodium hydroxide, 2% sodium sulfite and 0.05% potassium bromide. After development is completed, any unreacted dye developer is washed out of the photosensitive element, preferably with an alkaline washing medium or other medium in which the unreacted dye developer is soluble. The expression "toned" is used to designate photographic images wherein the silver is retained with the precipitated dye, whereas "monochromatic" is intended to designate dye images free of silver.

It should be noted that the dye developers of this medium are self-sufficient to provide the desired color image and do not depend upon coupling reactions to produce the desired color. They thus provide a complete departure from conventional photographic color processes in which the color is produced by a coupling reaction between a "color former" or "coupler" and the oxidized developing agent, as well as so-called auto-coupling processes in which color is obtained by a reaction of the oxidized developing agent with unoxidized developing agent.

It will be apparent that, by appropriate selection of the

image-receiving element from among suitable known opaque and transparent materials, it is possible to obtain either a colored positive reflection print or a colored positive transparency. Likewise, the inventive concepts herein set forth are adaptable for multicolor work by the use of special photographic materials, for example, film materials of the type containing two or more photosensitized elements associated with an appropriate number of image-receiving elements and adapted to be treated with one or more liquid processing compositions, appropriate dye developers suitable to impart the desired subtractive colors being incorporated in the photosensitized elements or in the liquid processing compositions. Examples of such photographic materials are disclosed in U.S. Patent No. 2,647,049 to Edwin H. Land.

As examples of useful image-receiving materials, mention may be made of nylon, e.g., N-methoxymethyl-polyhexamethylene adipamide, polyvinyl alcohol, and gelatin, particularly polyvinyl alcohol or gelatin containing a dye mordant such as poly-4-vinylpyridine. The image-receiving element also may contain a development restrainer, e.g., 1-phenyl-5-mercaptopetrazole, as disclosed in the copending application of Howard G. Rogers and Harriet W. Lutes, Serial No. 50,849, filed August 22, 1960.

The dye developers herein set forth are also useful in the formation of colored images in accordance with the photographic products and processes described and claimed in U.S. Patent No. 2,968,554, issued to Edwin H. Land on January 17, 1961.

The novel compounds herein disclosed are also suitable for use as dyes for textile fibres, such as nylon.

In the preceding portions of the specification the expression "color" has been frequently used. This expression is intended to include the use of a plurality of colors to obtain black.

My copending U.S. application, Serial No. 230,287, filed concurrently herewith, claims the photographic utilization of the novel compounds of the present invention.

Since certain changes may be made in the above products, compositions and processes without departing from the scope of the invention herein involved, it is intended that all matter contained in the above description shall be interpreted as illustrative and not in a limiting sense.

What is claimed is:

1. A compound of the formula:

wherein Ar is an aryl nucleus selected from the group consisting of benzene and naphthalene nuclei; each Z is selected from the group consisting of chlorine and lower alkyl; w is an integer from 0 to 3, inclusive; v is an integer from 0 to 2, inclusive; p is an integer from 1 to 2, inclusive; Y is a p-dihydroxyphenyl radical; and X_b is the radical of an azo dye coupler linked to said $-N=N-$ group.

2. 1-phenyl-3-methyl - 4 - [p-(hydroquinonylsulfonyl)-phenylazo]-5-pyrazolone.

3. 4-methoxy - 2 - [p-(hydroquinonylsulfonyl)-phenylazo]-1-naphthol.
